UNITED STATES PATENT OFFICE.

TORBJÖRN LINGA, OF WAUKEGAN, ILLINOIS, ASSIGNOR TO THE LINGA COMPANY, OF WAUKEGAN, ILLINOIS, A CORPORATION OF ILLINOIS.

CARBURETOR THERMOSTATIC NEEDLE VALVE.

Application filed March 8, 1920. Serial No. 364,120.

My invention aims to improve the performance or manner of functioning of carburetors, such as are used for supplying explosive gaseous mixtures to internal combustion engines or motors. As such appliances are now ordinarily constructed, when not supplied with proper thermostatic means the needle-valve which controls or governs the feed of fuel to the mixing chamber where the fuel and air become intermixed remains set at a suitable adjustment, unless manually temporarily displaced to facilitate starting of the motor, with the result that if the adjustment of the needle-valve is proper for ordinary running or service conditions it is not that which is best or well suited for starting the engine, such initial operation requiring a somewhat richer mixture. Conversely, if the needle-valve adjustment is set for easy starting of the engine, the gaseous mixture will be too rich in gasoline or other fuel for service conditions. Of course the motor and carburetor are usually relatively cold, sometimes extremely so, when the motor is first turned over and they gradually become much warmer and in some cases in fact quite hot under running conditions particularly in the summer or on long journeys as during touring or with heavy loads or steep grades.

The leading object and prime purpose of this invention is to care or compensate for all of these varying circumstances by automatically regulating or governing the degree of opening of the needle-valve port by improved means whereby the valve will be open more when the carburetor and engine are cold and will be open a less amount when such members are hot, thus assuring a proper or correct richness of mixture or suitable proportion of its ingredients under all conditions. This is accomplished by making the needle-valve of proper and suitable construction and thermostatic in its action so that its position or opening will vary with the amount of heat or degree of temperature to which it is subjected.

To this end the steel tapered point portion of the valve is mounted on the end of a rod of hard-rubber or other suitable material with a large co-efficient of expansion, such rod being carried, surrounded, and protected by the hollow threaded headed brass stem of the valve which screws into and is adjustable in a threaded opening in the car-

buretor. By reason of the greater expansion and contraction of the hard-rubber than of the metal of the carburetor, the valve-port with which the needle-valve coacts will be open a greater amount when the carburetor is cold than it will be when it is hot and by making the rubber-rod of a proper length a practically exact compensation for changes in temperature may be effected. By surrounding or encasing such rod in the metal threaded stem of the valve, breakage of the rod during use, insertion in or removal from the carburetor, or transportation, or shipment is effectively prevented as the stem constitutes a guard or shield covering the rod wholly or in part. It is desired to have the rod fit fairly snugly, but of course not too tightly, in the hollow stem thus assuring the proper position of the steel tapered point which it carries in the contraction and expansion movements of the rod, which by means of the confining and guiding action of the stem is prevented from warping or twisting out of its correct place.

To enable those skilled in this art to have a full understanding of the salient characteristics of the invention and its several advantages I have illustrated in the accompanying drawing forming a part of this specification a preferred and desirable embodiment of the invention like reference characters referring to the same parts throughout the several views of the drawing.

In this drawing:

Figure 1 is a vertical section through a carburetor equipped with the improved needle-valve, a portion of the appliance being unsectioned;

Figure 2 is a face view of the needle-valve; and

Figure 3 is a longitudinal section through the needle-valve on an enlarged scale.

Referring to this drawing it will be perceived that the carburetor, except for the new form and style of needle-valve, is of a well known construction, but it is to be understood that other structures of carburetors may be used to equal advantage.

This carburetor includes the usual fuel-chamber 10 equipped with a float 11 controlling the flow of liquid fuel, such as gasoline, thereto in order to maintain a constant and uniform liquid level in such compartment.

The improved thermostatic needle-valve 12 coacts with a nozzle or valve-port 13

through which the gasolene to be atomized is drawn by suction in the usual way. The part 14 is a so-called low-speed tube through which the needle-valve loosely extends permitting passage or flow of the gaseous mixture through the annular space between the two elements. The customary throttle 15 is operated by a suitable connection 16 and the choke-valve 17 is actuated by a wire 18 connected to its arm 19, by which two means, respectively, the power delivered by the engine is controlled and the richness of mixture upon starting the engine may be governed. In some cases this choke-valve 15 may be eliminated when my improved thermostatic needle-valve is employed, and in other cases it may be desirable to retain such choke-valve.

The improved needle-valve is threaded thru a split binder-nut 20 screwed into a threaded opening thru the wall of the carburetor, the needle-valve proper comprising a short pointed or conical-shaped steel terminal portion 21 into a threaded cavity 22 of which is fitted the reduced screw threaded end 22 of a hard-rubber or other suitable cylindrical thermostatic rod 23, the opposite reduced-diameter threaded end 24 of which is screwed into a socket 25 in the brass or other appropriate metal member 26 which has a knurled head 27 by which it may be easily manipulated and a long, hollow, externally-threaded stem or shank 28 desirably, but not necessarily, of a length to completely cover and shield the whole of the internal, more or less fragile, rubber-rod conveniently of a diameter only slightly less than that of the bore of the interior of such stem.

By means of such threaded stem or shank the needle-valve may be readily adjusted to position the pointed member 21 with reference to the valve-port by merely turning the handle 27, the coacting thread of the shank 28 and the internal thread of the nut 20 causing the needle-valve as a whole to advance toward or recede from the port. Obviously since the shank of the needle-valve metal member covers the rubber-rod it fully protects the latter from damage or injury and because of the relatively close fit be-

tween the rod and stem the latter outer element controls the position of the inner member preventing its displacement or distortion and maintaining the conical terminal element in proper and correct position with respect to its companion valve-port. The length of the rubber-rod is so chosen that the difference in expansion and contraction between the rod and the metal portions of the carburetor is such that the valve-port will be open the correct amount to deliver a proper richness of mixture for the starting of the motor when the carburetor is cold, and the expansion of the rubber-rod will be such that the degree of opening of the valve-port will be decreased or diminished as the carburetor heats up, thus maintaining at all times a proper proportion of the gaseous mixture ingredients depending upon the temperature of the carburetor and engine with which it is associated.

In many carburetors the advantages of this new invention may be had by merely removing the old threaded needle-valve and substituting the new thermostatic one in its place.

The invention is not limited or restricted to the precise and exact details of structure illustrated and described because these may be modified to a considerable extent without departure from the substance and essence of the invention and without the sacrifice of any of its substantial benefits and advantages.

I claim:

A thermostatic needle-valve construction of the character described, comprising in combination, a main-body having a head and a hollow externally screw-threaded shank, a hard-rubber rod accommodated in said shank and having a threaded connection at its inner end with said body, and a pointed valve having a screw-threaded mounting on the outer end of said rod, the bore of said shank being substantially the same as the diameter of said rod, said shank being of a length to completely enclose said rod, substantially as described.

TORBJÖRN LINGA.
